ILLUMINATED VANITY CASE

Edward P. Schreyer and Karl Peters, Milwaukee,
Wis.; said Peters assignor to said Schreyer

Application January 22, 1942, Serial No. 427,726

5 Claims. (Cl. 240—6.45)

This invention relates to improvements in illuminated vanity cases.

It has heretofore been proposed to have vanity cases equipped with electric lights, but these prior constructions have been too bulky to be practical and have involved difficult assembly work, rendering the cost of manufacture too high for this type of product.

It is a general object of the present invention to provide an illuminated vanity case which can be manufactured at low cost and which is of such compact size that it may be readily supported in the palm of the hand and will also occupy a minimum of space in a lady's handbag.

A further object of the invention is to provide a construction as above described wherein the entire electrical unit, including the bulb socket and battery, are formed in one unit positionable below the mirror and adjacent the hinge connection of the case, in the cover of the case, whereby the bulb throws a spotlight on the face of the user, which light is reflected back into the mirror.

A further object of the invention is to provide simple means whereby the bulb is automatically illuminated when the case is opened and whereby the circuit to the bulb is automatically broken whenever the case is closed.

A further object of the invention is to provide a construction as above described wherein there is an auxiliary cover for the battery and electrical unit, having an opening for registration with the bulb, said auxiliary cover being swingable on a hinge common to the hinge for the case to occupy a position in the cover between the inner edge of the mirror and the hinge connection of the case.

A further object of the invention is to provide a construction as above described wherein the cover of the case is formed with guiding and positioning lugs and projections and is so shaped as to permit quick assembly of the mirror and electrical unit within the cover, without the use of tools, with the parts held firmly in position.

A further object of the invention is to provide a vanity case construction wherein the base for the electrical unit is of wafer thinness, wherein the bulb socket is embodied as an integral part of a relatively flat contact strip, and wherein the cover of the case is recessed below the lower end of the bulb to readily accommodate the same without increasing the thickness of the case.

With the above and other objects in view, the invention consists of the improved illuminated vanity case and all its parts and combinations

as set forth in the claims, and all equivalents thereof.

In the accompanying drawing illustrating one complete embodiment of the preferred form of the invention, in which the same reference numerals designate the same parts in all of the views,

Fig. 1 is a plan view of the assembled vanity case in open condition;

10 Fig. 2 is a longitudinal sectional view taken on line 2—2 of Fig. 1;

Fig. 3 is a fragmentary plan view of the opened vanity case illustrating the cover side of the case with the auxiliary cover open and with the mirror and electrical unit in position, the battery being shown in dotted lines;

Fig. 4 is a view similar to Fig. 3 with the mirror and electrical unit removed;

15 Fig. 5 is a fragmentary sectional view on an enlarged scale taken on line 5—5 of Fig. 3;

Fig. 6 is a fragmentary detail view on an enlarged scale showing how the circuit from the battery is broken when the case is closed; and

20 Fig. 7 is a perspective view of the case in closed condition.

Referring more particularly to the drawing, the case generally comprises a cosmetic section 10 and a cover section 11 hinged together as at 12. Each of these sections is in the form of a hollow shell and is preferably formed by molding from a plastic or any other suitable material.

25 The section 10 has a transverse partition 13 dividing the interior of the section into two compartments 14 and 15. The compartment 14 is adapted to hold a desired cosmetic such as loose powder 16, and when loose powder is contained in the compartment 14 a cloth screen 17 may be removably fitted thereover. A powder puff 18 may be removably positioned over the screen 17.

30 Hingedly connected as at 19 on a line common to the hinge connection for the vanity case is an auxiliary cover 20. This cover 20 conceals the battery and electrical unit and is formed with a bulb opening 21. The auxiliary cover is normally positioned as shown in Figs. 1 and 2, and the portion which projects above the vanity case section 11, as shown in Fig. 2, is received in the compartment 15 when the vanity case is closed so that no material increase in thickness of the case is required in order to accommodate the battery and electrical unit. The compartment 15 also forms a space into which the auxiliary cover may be swung, as shown by the dotted lines in Fig. 2, when it is desired to open the auxiliary cover for access to the battery or electrical unit.

The auxiliary cover does not fit completely in the compartment 15, but rests on the shoulder 15' to afford space therebelow for the projecting light bulb when the case is closed. (See dotted line position of Fig. 2.)

Referring to the cover section 11 of the vanity case, and more particularly to Figs. 2 and 4, the interior thereof is formed with a transverse rib 22 which divides the interior of the cover into two shallow compartments 23 and 24. Projecting into the compartment 24 from the rib 22 are lugs 25. Each lug is stepped to form a shoulder 26 and a shelf 27, and at the inner end of the shelf 27 is a guiding incline 28 leading to the bottom of the compartment 24.

Adjacent to the hinge connection and opposite to the lugs 25 are stepped lugs 29 formed with shoulders 30 and with shelves 31. Disposed substantially centrally of the compartment 24 is a bulb recess 32 which appears as a projection 33 on the outside of the case, as shown in Fig. 7. This projection 33 may be worked into the exterior design of the vanity case, as shown in Fig. 7, to enhance the appearance.

The side walls of the compartment 23 of the cover section 11 are provided with guiding lugs 34 which are spaced above the bottom of the compartment 23 as shown in Fig. 2. A mirror 35 may be slid into assembled position (when the auxiliary cover 20 is in the dotted line position of Fig. 2 and when the electrical unit is removed). In sliding the mirror into position it rests on top of the partition 22, and the edge 36 of the mirror is guided by the curved bottom 37 of the compartment 23 to the final assembly position of Fig. 2. When in this position the lugs 34 overlap the side edges of the mirror and maintain the same in position.

The electrical unit consists of a thin sheet 38 of fibrous insulating material to which metallic contact members 39 and 40 are riveted. The contact strip 39 has an enlarged part 41 formed with a socket opening 42. The edges of the socket opening are formed with tabs which alternately project upwardly and downwardly as shown in Fig. 5. An upwardly projecting tab is designated by the numeral 43, and a downwardly projecting tab is designated by the numeral 44. The bent tabs form in effect a threaded socket for cooperation with the threads on the stem of the electric light bulb 45. Thus a socket is formed in the contact strip which does not necessitate an increase in thickness in the vanity case.

The lower end of the stem of the bulb 45 projects below the insulating sheet 38 and is accommodated in the recess 32 of the cover. The lower end of the bulb also makes contact with a yielding finger 46 which projects from the other contact strip 40. One end of the contact strip 40 is bent upwardly, as at 47, to normally contact, when the vanity case is open, the pole 48 of a small dry battery 49. The opposite end of the contact strip 39 is also bent upwardly and in addition laterally as at 50 to yieldingly and electrically engage the opposite end of the dry battery 49.

The electrical unit is inserted in position after the mirror 35 by sliding the front edge of the fiber sheet toward the lugs 25. This front edge will be guided upwardly by the lug inclines 28 into engagement with the shoulders 26 and beneath the inner edge of the mirror 35. The rear edge of the supporting sheet 38 will then rest on top of the shelves 31 of the lugs 29 and against the shoulders 30.

After the mirror and electrical unit are in position, the auxiliary cover is swung to the full-line position of Fig. 2 until a latch 51 on the free edge of the auxiliary cover snaps beneath the inner edge of the mirror 35, as shown in Fig. 2. When the auxiliary cover is in this position, the upper end of the bulb 45 projects through the bulb opening 21 in the auxiliary cover.

The auxiliary cover 20 is formed near one end 10 with an opening 52 which when the auxiliary cover is in the closed position of Figs. 1 and 2 is approximately over the upwardly bent end 47 of the contact strip 40. One of the marginal edges of the opening has an inwardly projecting flange 53 (see Figs. 2 and 6) which engages the end of the battery to prevent longitudinal shifting thereof.

In the compartment 15 of the vanity case section 10 there is a circuit-breaking lug 54 having 20 a wedge-shaped upper end. This lug is so positioned that when the vanity case is closed it enters the opening 52 of the auxiliary cover 20 and forces itself wedgingly between the battery pole 48 and the bent end 47 of the contact strip 25 to prevent the portion 47 of the contact strip from contacting the battery pole 48 when the vanity case is closed. This action is illustrated in 30 Fig. 6. The circuit-breaking lug 54 is, of course, formed of material which does not conduct electricity. It is obvious, therefore, that when the case is closed the electric light will be automatically shut off, and that when the case is opened the circuit-breaking lug 54 will be pulled out of the position of Fig. 6 and will allow the contact 35 portion 47 to yieldingly engage the battery terminal 48 and complete the electrical circuit. When the circuit is complete the current will flow from one end of the battery through the contact strip 40, yielding tongue 46, to the lower 40 end of the bulb; from the outside of the bulb through the contact strip 39, bent portion 50 thereof, to the bottom of the battery casing forming the other terminal of the battery.

The case is detachably held in closed position 45 by cooperating snap latches 55 and 56, and the opening of the case is facilitated by pressing inwardly on the sides of the case as at 57.

The arrangement of the electric light bulb is 50 such that when the powder containing section is held substantially horizontally in the palm of the hand with the fingers of the hand holding the mirror containing section at an angle, the bulb will be directed toward the face in such a manner as to throw a spotlight thereon, while the mirror is held in such a position that it may be used to assist in applying the powder.

It is also apparent that the electrical unit and 55 automatic circuit breaking construction is such as to provide for a minimum of parts to be accommodated in the case with a minimum of bulk. It is also clear that the electrical unit and mirror can be quickly assembled in the cover of the case without the use of tools, and that the electrical unit itself can be completely assembled 60 in a convenient manner before installation in the vanity case. The arrangement is also such as to permit an inexperienced user to easily replace the battery or light bulb.

Although only one form of the invention has 65 been shown and described, it is obvious that various changes and modifications may be made without departing from the spirit of the invention, and all of such changes are contemplated 70 as may come within the scope of the claims.

What we claim is:

1. A vanity case comprising two hinged together sections, one of said sections having a transverse rib and having side wall lugs positioned toward the free edge of the section from said rib, a mirror supported on said rib and beneath said lugs and being removable by sliding movement, the inner edge of the mirror terminating short of the hinged edge of the section, and an electric light unit positioned between said rib and the hinged edge of the section.

2. A vanity case comprising two hinged together sections, one of said sections having a transverse rib and having side wall lugs positioned toward the free edge of the section from said rib, a mirror supported on said rib and beneath said lugs and being removable by sliding movement, the inner edge of the mirror terminating short of the hinged edge of the section, and an electric light unit positioned between said rib and the hinged edge of the section and overlapped by the inner edge of the mirror.

3. A vanity case comprising two hinged together sections, a mirror in one of said sections having its inner edge terminating short of the hinged edge of the section, means for elevating the inner edge of the mirror from the bottom of the case section, lugs on the case section bottom beneath the inner edge of the mirror, and an electric light unit including a thin base sheet

having an edge slideable into position beneath the inner edge of the mirror and into engagement with said lugs.

4. A vanity case comprising two hinged together sections, a mirror in one of said sections having its inner edge terminating short of the hinged edge of the section, means for elevating the inner edge of the mirror from the bottom of the case section, stepped lugs on the case section bottom beneath the inner edge of the mirror, an electric light unit including a thin base sheet having an edge slideable into position beneath the inner edge of the mirror and into engagement with said lugs, said lugs having an inclined portion for guiding the edge of the base sheet onto the steps of said lugs.

5. A vanity case comprising two hinged together sections, a mirror in one of said sections having its inner edge terminating short of the hinged edge of the section, means for elevating the inner edge of the mirror from the bottom of the case section, lugs on the case section bottom beneath the inner edge of the mirror, an electric light unit including a thin base sheet having an edge slideable into position beneath the inner edge of the mirror and into engagement with said lugs, and positioning lugs cooperable with the opposite edge of the base sheet.

EDWARD P. SCHREYER.
